UNITED STATES PATENT OFFICE.

EDWARD ROANE MELTON, OF WASHINGTON, DISTRICT OF COLUMBIA.

COOLING APPARATUS FOR INKING-ROLLERS.

1,048,193.

Specification of Letters Patent. Patented Dec. 24, 1912.

Application filed July 28, 1911. Serial No. 641,026.

To all whom it may concern:

Be it known that I, EDWARD R. MELTON, a citizen of the United States residing at Washington, in the District of Columbia, have invented certain new and useful Improvements in Cooling Apparatus for Inking-Rollers; and I do hereby declare the following to be a full, clear, and exact description of the invention, such as will enable others skilled in the art to which it appertains to make and use the same.

My invention relates to a new and useful device for cooling the inking rollers of printing presses.

15 An object of my invention is to provide an improved cooling device for inking rollers of printing presses which will insure a proper and uniform carrying of ink thereby and minimize all wear and deterioration of 20 such rollers.

A further object of my invention is to provide a simple and efficient cooling device adapted to be conveniently applied to the existing types of inking rollers.

25 In the drawings accompanying and forming a part of this application, similar reference characters indicate similar parts thereof.

Figure 1 is a transverse section of a portion of a printing press showing my improved cooling device attached thereto; Fig. 2 is an end view of the rollers and supporting brackets therefor showing improved device attached, and Fig. 3 is a detail perspective view of the air-supply pipe of my cooling device.

Referring to the drawings, 1 indicates any usual inking rollers coöperating with a reciprocating bed 2 and provided with a distributing roller 3. The bed is shown provided with a rack 4 for actuating a pinion 5 on a stub shaft 6 journaled in a frame 7, said shaft being provided with a worm 8 threaded through a slide 9 which slidably 45 engages a guide 10.

The spindle 11 of a distributing roller 3 extends slidably through journal bearings 13 in the frames 7 and is provided with collars 14 for engaging opposite sides of a 50 saddle 15 carried by the slide 9.

The contacting rollers 1 and 3 are shown rotated in a well known manner by a pinion 16 secured to the spindle 11 in sliding mesh with the pinion 5.

An air-supply pipe 17 is slidably supported on saddles 18 on the frames 7 and provided with any suitable flexible connection 19 with a source of air under pressure. A head 20 is secured on one end of the pipe 17 and provided with a yoke or socket 21 extending between the collars 14 on the spindle 11 whereby said pipe will be reciprocated by the slide 9 synchronously with a distributing roller 3. The air-supply pipe 17 is provided with a series of nozzles 22 for 65 directing air jets against the rollers 1.

From the above description it will be understood that my invention provides an improved construction in which the nozzles 22 on the reciprocating pipe 17 will direct 70 cooling jets of air uniformly along the entire surface of the rotating inking rollers.

The inking rollers of existing types of printing presses being generally composed of some plastic material often become heated 75 and softened as a result of friction caused by the rotating and reciprocating motion of the distributing roller. The result of this heating and softening is to cause an uneven distribution of ink by said rollers, and also a 80 considerable amount of wear upon the rollers themselves. This uneven distribution of ink and the wear upon the rollers would be greatly minimized by the use of the above described means of cooling.

Having described my invention what I claim and desire to secure by Letters Patent is—

1. In combination with an inking apparatus consisting of rotating rollers and a 90 roller mounted for reciprocation longitudinally of said rotating rollers, an air pipe having nozzles directed toward said rotating rollers, and means to reciprocate said air pipe synchronously with said reciprocating 95 roller.

2. In an inking apparatus, rotating rollers, a relatively reciprocating roller mounted to move longitudinally of said inking rollers, an air pipe slidably mounted and having nozzles thereon directed toward said rotating rollers, and means connecting said reciprocating roller and the air pipe to cause said air pipe and the reciprocating roller to move synchronously.

3. An inking apparatus comprising rotating inking rollers, a relatively reciprocating roller mounted to move longitudinally of

said rotating rollers and having a shaft extending from its end, a grooved collar mounted on said shaft, means engaging said collar to reciprocate said roller, an air pipe 5 mounted to slide longitudinally and having nozzles directed toward the rotating rollers, and a head secured to said air pipe and having a yoke thereon engaging the groove in

said collar to move said air pipe synchronously with the reciprocating roller. 10

In testimony whereof I affix my signature in presence of two witnesses.

EDWARD ROANE MELTON.
